(57) **CLAIM**

The ornamental design for a powercore module, as shown and described.

DESCRIPTION

FIG. 1 is a front, top, perspective view of a powercore module.

FIG. 2 is a top plan view thereof.

FIG. 3 is a bottom plan view thereof.

FIG. 4 is a front view thereof.

FIG. 5 is a rear view thereof.

FIG. 6 is a right side view thereof; and,

FIG. 7 is a left side view thereof.

No claim is made to portions which are not shown. The dash-dash disclaim lines indicate portions to which no claim is made. The surface is lightly lined for contour.

1 Claim, 7 Drawing Sheets
